UNITED STATES PATENT OFFICE.

CHRISTOPHER STEWART ROBERTSON, OF JACKSONVILLE, FLORIDA.

SIDE WINDOW FOR AUTOMOBILES.

Application filed August 5, 1921. Serial No. 490,023.

To all whom it may concern:

Be it known that I, CHRISTOPHER S. ROBERTSON, a citizen of the United States, residing at Jacksonville, in the county of Duval and State of Florida, have invented a new and useful Side Window for Automobiles, of which the following is a specification.

This invention relates to a side window for automobiles and is designed more particularly as an improvement upon the structure disclosed in Patent No. 1,383,027 issued to me on June 28, 1921.

It is an object of the present invention to provide side windows which can be readily attached to or removed from the side doors of an automobile, these windows serving completely to close the space between the sides of the body and of the automobile top although any one of the windows can be slid backwardly relative to the supporting doors for the purpose of securing ventilation.

Another object is to provide windows which afford a clear unobstructed view for the driver and which will, in no sense, detract from the appearance of the vehicle but, on the contrary, render the same more attractive.

A still further object is to provide side windows which can be stored readily in the vehicle when they are not in use, there being means for finishing the tops of the doors after the windows have been removed so that the doors will have the appearance of ordinary ones.

A further object is to provide side shields or windows for open body or touring types of automobiles which can be applied readily to the doors thereof to replace the ordinary side curtains and at the same time give an unobstructed view for the occupants of the car and thus greatly reduce the danger of accidents often caused by the obstructions of the view caused by side curtains of the ordinary type.

A further object is to provide side shields or windows which, being capable of independent movement with respect to each other and to the doors, can be partly or entirely closed without interfering with the operation of the doors and will not only give the car the appearance of a permanent or sedan type of top, but also permits the change to be made to the sedan type without removing the ordinary top and replacing it with a permanent

or built in type of top such as requires remodeling and involves the owner in considerable additional cost.

With the foregoing and other objects in view which will appear as the description 60 proceeds, the invention resides in the combination and arrangement of parts and in the details of construction hereinafter described and claimed, it being understood that, within the scope of what is claimed, changes in 65 the precise embodiment of the invention shown can be made without departing from the spirit of the invention.

In the accompanying drawings the preferred form of the invention has been shown. 70

In said drawings—

Figure 1 is a side elevation of an automobile having the present improvements combined therewith.

Figure 2 is an enlarged section on line 75 2—2, Figure 1.

Figure 3 is an enlarged section on line 3—3, Figure 2.

Figure 4 is a section on line 4—4, Figure 1, said section being enlarged. 80

Figure 5 is a vertical section through a portion of a door and showing a slightly modified form of structure combined therewith, parts being broken away.

Figure 6 is a section on line 6—6, Figure 5. 85

Figure 7 is a detail view of the removable cap used in connection with a door after a window has been removed therefrom.

Referring to the figures by characters of reference 1 designates a vehicle body having the usual top 2, the space between the back portion of the body and the top being provided with a curtain 3 of the usual type which can be placed in position when desired. Each of the doors 4 is provided in its upper edge with a longitudinal groove 5 which extends through the free end of the door and up to a point removed from the hinged end thereof as shown particularly by dotted lines in Figure 1 and by full lines 95 in Figure 3. The walls of the groove are formed with longitudinal channels 6 at the bottom thereof and seated within recesses 7 in said walls near the upper end of the groove are leaf springs 8. 100

Side posts 9 are erected on the body between the front portion of the cover 2 and the rear portion of the hood 10, these side posts being formed at their outer sides with longitudinal flanges 11 extending rearward- 110

ly as indicated by a dotted line in Figure 1 and in section in Figure 4. These posts do not in themselves constitute any part of the present invention but have already been disclosed in a co-pending application filed by me on July 15, 1921, Serial No. 484,980.

Each window adapted to be supported above the front door 4 of an automobile is formed of a frame 12 carrying a glass light 10 13. The front of the frame is inclined so that when the frame is mounted on the top of the door 4 the front edge of said frame will lie parallel with the adjacent post 9. The top of the frame 12 is straight and has 15 secured upon it a laterally extending plate 14 coextensive in length with the top of the frame and so proportioned as to fit snugly under the side edge of the top 2 so as thus to prevent snow or the like from drifting 20 into the car between the straight top of the frame 12 and the curved side of the top 2. The bottom of the frame 12 has its outer side so shaped as to shed moisture over the outer side of the door 4 thereunder, this portion of the frame being indicated at 15.

Extending downwardly from the bottom of the frame 12 is a longitudinally extending fin 16 the width of which is approximately the same as the width of the groove 30 5 while the height thereof is approximately the same as the depth of said groove. Ribs 17 are provided along the sides of the fin at the lower edge thereof and are adapted to fill the channels 6. The fin 16 does not 35 extend the full length of the bottom of the frame but is so proportioned that when it is inserted longitudinally into the groove 5 with one end against the end wall of the groove, as shown in Figures 1 and 3, there 40 will be a space between the fin and the other or open end of the groove. When the fin is thus located the inclined front end of the frame 12 will bear against the post 9 and be lapped by the flange 11. At the same 45 time the plate 14 will fit snugly under the side of the top 2. Obviously the window cannot be placed in position until after the door 4 has been opened so as to expose the end of the groove 5. The fin can then be 50 inserted into the groove and will wedge between the springs 8 which serve to tightly grip the fin and hold the parts from rattling. When the door is closed the window will 55 assume a position upon the top of the adjacent portions of the side of the body 1 and a tight connection will be made between the frame and the adjacent parts of the body, post and top. Secured to the back edge of the frame 12 is a plate or shield 18 the width 60 of which is slightly greater than the distance between the fin 16 and the open end of the groove 5. This shield 18 constitutes means for closing the space between the back of the frame 12 and the window or 65 curtain in rear thereof. If the automobile

has one seat this shield will lap the curtain 3 but if the machine has two seats the shield will lap the front end of a window frame 19 mounted on the rear door. This second frame is similar to the frame 12 with the 70 exception that its front end is vertical instead of inclined. The frame is detachably mounted on the door in the same manner as has heretofore been described.

When the windows are not in use they 75 can be stored at suitable places provided therefor within the body of the car. When they are to be used the doors are opened and the windows are applied thereto in the manner hereinbefore described. If the doors 80 are closed the front windows can be moved backwardly a distance equal to the distance between the fins 16 and the rear ends of the grooves 5, this movement being sufficient to withdraw the front ends of the frames 12 85 from behind the flanges 11 on the posts 9. Thus ventilation can be obtained. If desired the front windows can be left against the posts 9 and the rear windows moved backwardly from behind the guard plates 16, 90 thus to afford ventilation.

Instead of having the window frames integral with or fixedly connected to the fins 16, fins 20 such as shown in Figures 5 and 6 can be inserted into the door grooves as 95 heretofore explained. Each of these fins can be provided with an upstanding stud 21 and the bottoms of the frames 22 can be provided with sockets 23 to receive the studs. Thus the frames can be swung upon the 100 studs and relative to the fins. Consequently by swinging the frames they can be used as supplemental side wind shields and ventilation can be obtained both by swinging the windows and by sliding them as before 105 pointed out. Set screws 24 can be used for fastening the frames against rotation on the studs and by providing annular grooves 25 in the studs to receive the set screws the frames can be held against upward withdrawal from the studs.

When the side windows are not in use a cap strip such as shown in Figure 7 can be placed in engagement with each door. This cap strip includes a top portion or sill 26 115 of the same length as the door. A fin 72 extends downwardly from this top portion and is insertible into the groove 5 so as to fill it completely. Ribs 28 are formed on the fin for the purpose of 120 filling the channels 6. Thus the doors will present a finished appearance when the windows are not in use and it will not be possible for dirt to collect in the grooves and interfere with the insertion of 125 the fins 16 or 20. These cap strips can be stored within the vehicle at convenient places while the windows are in use.

What is claimed is:—

1. The combination with a vehicle body, 130

- a wind shield side post and a top, of a door having a longitudinal groove in the top thereof, a window including a frame and a transparent portion secured therein, and a 5 fin extending downwardly from the frame and insertible longitudinally into the groove in the door to position the frame between the door and top and back of the post, said fin being shorter than the groove, and said 10 frame and fin being slidable relative to the door to vary the position of the frame relative to the post.
2. The combination with a vehicle body, and front and rear doors having grooves in 15 the tops thereof, of front and rear window frames mounted on the respective doors, fins depending from the frames and insertible longitudinally into the respective grooves, said fins being shorter than and slidible 20 within the grooves while the doors are shut, and a guard plate upon one of the frames
- and lapping the next adjoining frame, said frames being normally spaced apart.
3. The combination with a vehicle body, of a door having a longitudinal groove in 25 the top thereof opening at one end through one side edge of the door, a fin insertible longitudinally into the groove, cooperating ribs and channels extending longitudinally of the fin and the walls of the groove respectively for holding the fin against upward withdrawal from the groove, a window frame on the fin and adapted to be supported by the door, and a swivel connection between the frame and fin. 30
- 35
- In testimony that I claim the foregoing as my own, I have hereto affixed my signature in the presence of two witnesses.

CHRISTOPHER STEWART ROBERTSON.
